[57] CLAIM

The ornamental design for a power tool table, substantially as shown and described.

DESCRIPTION

FIG. 1 is a front perspective view of a power tool table showing our new design;

FIG. 2 is a fragmentary, front perspective view taken along the plane 2—2 in FIG. 1 shown broken away to better illustrate the interior configuration of the leg, it being understood the other three legs are identical;

FIG. 3 is a top plan view thereof;

FIG. 4 is a front elevational view thereof;

FIG. 5 is a left side elevational view thereof, the right side being a mirror image thereof;

FIG. 6 is a rear elevational view thereof.
